REFRIGERATOR SEALING STRIP

Robert S. Taylor, Evansville, Ind., assignor to
 Electrolux Servel Corporation, New York, N. Y.,
 a corporation of Delaware

Application November 14, 1930, Serial No. 495,553

4 Claims. (Cl. 20—35)

This invention relates to refrigerators and more particularly to those in which the refrigerating compartment has an aperture in one wall thereof through which the evaporator of a refrigerating apparatus unit is inserted when the unit is assembled with the refrigerator.

In a refrigerator of this construction, the evaporator is mounted on a section of heat insulated wall which, in turn, is mounted as part of the refrigerating apparatus unit. When the unit is assembled with the refrigerator cabinet, the evaporator is inserted through the aperture in the refrigerating chamber wall and the section of heat insulated wall upon which the evaporator is mounted acts as a closure member for the aperture. Formerly, the seal between the closure member and the refrigerating compartment wall was made with a cement, such as Dum-Dum or Tilette. Both of these cements have an odor which is a very undesirable feature in a refrigerator and, moreover, when it is desired to remove the refrigerating apparatus unit it is necessary to break this seal and make a new one with fresh cement when the unit is replaced.

It is an object of this invention to provide a seal between a refrigerator wall having an aperture therein and a closure member for said aperture which seal will not require replacement when the closure member is withdrawn and replaced. A further object is to provide a seal that is of asthetic appearance and presents only plane surfaces which are easily cleaned.

Further objects and advantages will be apparent from the following description taken in connection with the accompanying drawing wherein

Fig. 1 is a fragmentary vertical section of a refrigerator wall having an aperture therein and a seal, constructed in accordance with this invention, between the refrigerator wall and a closure member in said aperture,

Fig. 2, a fragmentary front elevation of the refrigerator wall and seal shown in Fig. 1, and

Fig. 3, a detailed cross-section of the seal secured in position.

A refrigerating chamber wall 10 has an aperture 11 therein and is constructed with a frame 12 around the edge of said aperture. The side of the wall toward the refrigerating compartment is covered with a sheet metal liner 13. A closure member for the aperture 11 comprises a plate 14 on which is mounted a section of heat insulating wall 15 conforming generally to the outline of the aperture. The section of wall 15 has a liner or shield plate 16 on the side toward the

refrigerating chamber. An evaporator 17 is mounted on the closure member by some means such as bracket 18 and bolts 19 so as to be positioned within the refrigerating chamber when the refrigerating apparatus unit of which the evaporator is an integral part is secured in position. Around the closure member, between the edge thereof and the edge of the refrigerating chamber wall around the aperture therein, is a joint or clearance space 20.

Where formerly a cement was used to seal this joint, this invention contemplates a seal which consists of three parts. A member 21 of some easily cleaned and rust resisting material, such as chromium plated zinc or Monel metal, which, for the purposes of this description, is called the liner opening sleeve trim, is permanently mounted around the inner edge of the aperture in the refrigerating chamber wall by a band 22 of resilient material fastened at one edge to the sleeve trim 21 and tacked or otherwise fastened at its other edge 23 to the refrigerator wall frame 12 around the aperture. A gasket 24 of sponge rubber or other suitable material is secured between the liner of the refrigerator wall and the sleeve trim 21 and another gasket 25 of similar material is secured around the under side of the sleeve trim 21 as by crimping, between the edge of the sleeve trim 21 and the fastening band 22.

When the refrigerating apparatus unit is secured in the refrigerator cabinet, the closure member will be positioned within the aperture 11 of the refrigerating chamber wall and the edges of shield plate 16 of the closure member will bear against the gasket 25. The seal is so positioned in relation to the edge of the aperture that when the closure member is positioned therein both gaskets 24 and 25 will be slightly compressed, effectively sealing the joint. Gasket 25 is compressed directly by the pressure of the closure member when the latter is in position and the gasket 24 is compressed indirectly by the pressure of the closure member acting through the sleeve trim 21 and the resilient metal band 22. If desirable, gasket 24 may be omitted leaving a clearance space between the liner 13 and the sleeve trim 21. An additional gasket 26 may be provided between the plate 14 and the refrigerator wall 10 to prevent circulation of air in the space 20 and the consequent likelihood of moisture accumulation therein.

It will be obvious to those skilled in the art that various other changes may be made in the construction and arrangement without departing from the spirit of the invention and therefore

the invention is not limited to what is shown in the drawing and described in the specification but only as indicated in the following claims.

I claim:

- 5 1. In a refrigerator cabinet including a wall having an aperture therein and a removable closure member within said aperture, a seal for the clearance space between the wall and said closure member and comprising a strip resiliently mounted around the edge of said aperture and overlapping both the wall around said aperture and said closure member, a compressible gasket between said strip and the portion of the wall around said aperture overlapped by said strip, and a second compressible gasket between said strip and the edge of said closure member overlapped by said strip, said second gasket being secured to said strip.
- 10 2. A refrigerator cabinet having an aperture in a wall thereof, a wall section adapted to close said aperture, a seal for the joint between the wall section and the cabinet comprising a sleeve trim having a crimped edge, a band of resilient material having one edge fastened to said sleeve trim and its other edge fastened to the wall between the wall and wall section, and gasket means sealing the joint between the sleeve trim and the cabinet wall and between the sleeve trim and the wall section, the crimped edge of the sleeve trim
- 15 30 serving to retain the gasket means in position.

3. In a refrigerator, a thermally insulated cabinet having an aperture in a wall thereof to permit insertion and removal of a cooling element of a refrigeration apparatus, a removable closure member in said aperture and through which extend connections to said cooling element, and a seal member resiliently mounted around the edge of said aperture within said cabinet by means of a portion extending into a clearance space between said closure member and wall and secured to said wall, said seal member overlapping both said closure member and the wall adjacent said aperture, and gaskets between said seal member and the wall and between said seal member and said closure member.

4. In a refrigerator, a thermally insulated cabinet having an aperture in a wall thereof to permit insertion and withdrawal of a cooling element of a refrigeration apparatus, a removable closure member in said aperture and through which extend connections to said cooling element, and a seal for the clearance space between said closure member and wall comprising a member overlapping both said closure member and the wall adjacent said aperture within said cabinet and secured to said wall by means of a resilient portion projecting into said clearance space.
